UNITED STATES PATENT OFFICE.

ARTHUR M. WIGHT, OF NEW YORK, N. Y.

BANDING-TOOL.

1,070,567.

Specification of Letters Patent. Patented Aug. 19, 1913.

Application filed January 5, 1912. Serial No. 669,705.

To all whom it may concern:

Be it known that I, ARTHUR M. WIGHT, citizen of the United States, residing at New York, in the county of New York and State of New York, have invented a certain new and useful Improvement in Banding-Tools, of which the following is a full, clear, concise, and exact description.

My invention relates to banding tools and its object is to provide a tool of simple construction in which the ends of a wire band can be quickly and easily secured to the co-operating jaws and in which said co-operating jaws may be easily opened apart to stretch the wire taut, and the tool then manipulated to twist the ends of the wire together.

The several features of my invention may be more readily understood by reference to the accompanying drawings, in which—

Figure 1 is a side elevation of the preferred embodiment of my invention, the tool being shown in position ready to begin the tightening of the wire about the box; Fig. 2 is a view similar to that of Fig. 1 of the opposite side of the tool; Fig. 3 is an end elevation of the tool shown in Figs. 1 and 2; Fig. 4 is a side elevation of a simplified form of tool embodying certain features of my invention, and Fig. 5 is an end elevation of the tool shown in Fig. 4.

Similar letters of reference refer to similar parts throughout the several views.

The two embodiments of my invention shown in Figs. 1, 2 and 3 and in Figs. 4 and 5, respectively, in general operate on the same principle, but in order to provide greater power I have introduced pawl and ratchet mechanism into the former in order to intensify the leverage and thereby to enable the operator to apply a wire of greater diameter to boxes carrying heavy loads. Since the tool shown in Figs. 4 and 5 embodies in simple form certain of the features shown in Figs. 1, 2 and 3, such simple form of tool will be described first.

Referring to Figs. 4 and 5, the tool consists of two levers 1 and 2 pivotally connected by a pin 3. The point of pivotal connection of the two levers is at the end of the lever 2, but is located between the handle of the lever 1 and the curved jaw 4 provided upon the inner end of the lever 1. The handle 2 is likewise provided with a curved jaw 5, said jaw, however, being carried by a downwardly extending post 6 pro-

jecting from the lever 2 intermediate the ends of said lever. The jaw 5 is adapted to be supported upon the surface of the box 7 which is being banded, and hence constitutes a supporting means for the tool. The jaw 5 is preferably of segmental shape and is curved rearwardly toward the handle of the lever 2 and is provided at its rear or outer end with claws 8, between which is provided a notch for receiving the wire 9. Located immediately above the claws 8 is an end-retaining post 10 about which the end of the wire 9 is looped. The outer end of the jaw 4 is likewise provided with claws 11 between which is provided a notch 12 for receiving the opposite end of the wire 9. Upon one side of the jaw 4 are located two adjacent end-retaining posts 13, 14, about which the ends of the wire are adapted to be drawn to secure said wire to said jaw 4.

In operation the tool is placed upon its side on top of the box 7 with the handle of the lever 2 extending toward the operator, and with the handle of the lever 1 pushed apart so that the heel 15 thereof will come in contact with the under surface of the lever 2. The end of the wire 9 is then provided with a loop which is placed about the post 10. The wire is then passed through the notch between the claws 8 around the curved surface of the jaw 5 and from thence around the box 7 in the direction indicated by the arrow, the opposite end of the wire passing around the box, as indicated by the arrow, crossing itself approximately at the jaw 5, and is then brought underneath the jaw 4, through the notch 12 provided between the claws 11, and from thence about the posts 13 and 14, as shown in Fig. 4. While it is easy to form a loop in one end of the wire adapted to slip over the post 10 it would be comparatively difficult to form a similar loop in the opposite end of the wire, whereas by carrying the wire around the posts 13 and 14, in the manner shown, that end of the wire is likewise securely held against slipping.

After the ends of the wire band are secured to the tool in the manner described, the operator grasps the handles of the two levers and turns the tool so that it rests upon its jaw 5. The lever 1 is then drawn toward the lever 2 until said lever 1 assumes substantially a vertical position, as shown in Fig. 4, in which position the wire band 9 has been drawn sufficiently taut. While the

tool is in this position the handle 2 is swung around to give a half turn or twist to the two ends of the wire to hold the same together under tension until said ends can be 5 otherwise suitably secured together. After such twist or half turn is given to the ends of the wire and the tension thus taken from the two levers, the depression of the handle of the lever 2 will release the loop from the 10 post 10, and the other end of the wire can then be readily released from the jaw 4. The ends of the wire are then clipped to suitable length.

It will be noted that in order to increase 15 the leverage as the tension on the wire increases, the curvature of the jaw 4 is such that the heel 15 thereof is nearer the pivot 3 than the outer end of said jaw. It follows, therefore, that during the operation of the 20 lever to stretch the wire the bearing of said wire upon the curved bottom of the jaw 4 gradually passes toward the heel 15, thus, as the strain increases, correspondingly increasing the leverage to the advantage of the 25 operator.

As has been stated the tool shown in Figs. 1, 2 and 3 has many features in common with the tool shown in Figs. 4 and 5. Therefore for convenience, in the description of 30 the preferred form of my invention, the parts corresponding to those already described in connection with Figs. 4 and 5 have been given the same reference numerals as heretofore but with a distinguishing 35 index letter.

Referring now to the preferred embodiment of my invention shown in Figs. 1, 2 and 3, the two levers 2^a and 1^a are pivotally connected by a pin 3^a. As in the form 40 hereinbefore described the lever 2^a is provided with a curved jaw 5^a carried by a downwardly extending post 6^a projecting from the lever 2^a intermediate the ends thereof. Said jaw is provided with the post 45 10^a and the claws 8^a corresponding in structure and functions to the post and claws hereinbefore described.

The jaw 4^a is in the form of a segment of a disk which is pivoted at its center, for 50 which purpose it is provided with a stub axle 16 upon which said disk is keyed or otherwise secured. The stub axle 16 is journaled in one end of a swinging arm 18. Said arm 18 is pivoted at 29 upon the lever 55 2^a intermediate the post 6^a and the pivot pin 3^a, and is thus adapted to be swung upon its pivot 29 for purposes hereinafter to be described.

Opposite the segment 4^a and integral 60 therewith is a segment 17 having a toothed periphery which normally meshes with a pinion wheel 19. The pinion 19 is secured to the pivot pin 3^a and likewise secured to said pin 3^a is a ratchet wheel 20. The lever 65 1^a is provided with a stepping pawl 21 piv-

oted thereto and arranged when the lever 1^a is moved away from the lever 2^a to engage and turn the ratchet wheel 20 in a well known manner. A retaining pawl 22 is pivoted upon the end of the lever 2^a and is adapted to hold the ratchet wheel 20 in its operated position during the reverse stroke of the lever 1^a. Thus by manipulating the lever 1^a back and forth and thereby turning the pinion wheel 19 the jaw 4^a is caused to turn, thereby drawing the wire 9 taut. 70 75

In Fig. 1 the tool is shown in position ready to begin the tightening of the wire 9 about the box 7, in which position the heel 15^a is in engagement with a stop 23 carried by the lever 2^a. By operating the handle 1^a back and forth, as just described, the segment 4^a is turned about its pivot 16 and the wire is thus drawn tight about the box. 80 85 When the wire band has been drawn sufficiently taut, the lever 2^a is swung around to give a half turn or twist to the two ends of the wire in the same manner as has been heretofore described. The ends of the wire 90 are then released from the post 10 and the posts 13^a and 14^a. It will be understood that the structure and function of the posts 13^a and 14^a, the claws 11^a and the notch 12^a are similar to those hereinbefore described 95 in connection with the simpler type of tool.

In order that the jaw 4^a may be restored to its initial position shown in Fig. 1, said jaw is, as heretofore stated, pivoted upon a swinging arm 18. Said arm is normally held in the position shown in full lines in Fig. 2 by a catch 24 which engages with the upper surface of an extension 25 of the lever 18. The catch 24 is pivoted upon the lever 2^a by a pin 26 and is normally held by a leaf spring 27 in engagement with the projection 25. However, by pressing down upon the catch 24 against the tension of the spring 27, said catch is removed from engagement with the projection 25 and the arm 18 can be swung into the position shown in dotted lines in Fig. 2 thereby throwing the teeth of the segment 17 out of gear with the pinion wheel 19. A coiled spring 28 thereupon acts to return the jaw 4^a into engagement with the stop 23. Thereupon the lever 18 is depressed and the extension 25 thereof is reengaged by the catch 24, thus again bringing the teeth of the segment 17 into engagement with the pinion 19. The 110 tool is thus restored to its normal or initial position. 115 120

What I claim is:

1. A banding tool comprising a pair of co-operating jaws and means for operating the 125 same, said jaws being provided with notches in their outer ends for receiving the opposite end portions of a wire band, and also with securing means for holding the ends of the wire which extend beyond said notches. 130

2. A banding tool comprising a pair of co-operating segmental jaws and means for operating the same, said jaws being provided with notches in their outer ends for receiving the opposite end portions of a wire band, and also with securing means for holding the ends of the wire which extend beyond said notches.
3. A banding tool comprising a pair of co-operating jaws and means for operating the same, said jaws being provided with notches in their outer ends for receiving the opposite end portions of a wire band, and also with end-retaining posts located in proximity to said notches.
4. A banding tool comprising a pair of co-operating segmental jaws and means for operating the same, said jaws being provided with notches in their outer ends for receiving the opposite end portions of a wire band, and also with end-retaining posts located in proximity to said notches.
5. In a banding tool, the combination with a lever provided intermediate its ends with a downwardly and rearwardly extending jaw adapted to constitute a support for said tool, the rear end of said jaw being notched to receive the end of a wire band and provided with an end-retaining post located above the notch; of a pivoted jaw co-operating with said first mentioned jaw, said pivoted jaw being notched at its outer end and provided with a pair of adjacent end-retaining posts; and means for operating said pivoted jaw.
6. In a banding tool, the combination with a lever provided intermediate its ends with a downwardly extending jaw adapted to constitute a support for said tool, said jaw being provided with means for holding one end of a wire band; of a segmental-shaped pivoted jaw co-operating with said first mentioned jaw, said pivoted jaw being notched at its outer end to receive the opposite end of said wire band and being also provided with means for securing the wire to said pivoted jaw; and means for operating said pivoted jaw.
7. In a banding tool, the combination with a lever provided intermediate its ends with a downwardly extending post terminating in a rearwardly extending segmental-shaped jaw, the rear end of said jaw being notched to receive the end of a wire band and provided with an end-retaining post located above the notch; of a segmental-shaped pivoted jaw co-operating with said first mentioned jaw, said pivoted jaw being notched at its outer end to receive the opposite end
- of said wire band and being also provided with a pair of adjacent end-retaining posts; and means for operating said pivoted jaw.
8. In a banding tool, the combination with a lever provided intermediate its ends with a downwardly extending jaw adapted to constitute a support for said tool; of a pivoted jaw co-operating with said first mentioned jaw; an operating lever pivoted to said first mentioned lever; gear mechanism interconnecting said operating lever and said pivoted jaw, whereby the manipulation of said operating lever rotates said pivoted jaw; and means for throwing said pivoted jaw into or out of operative relation with said operating handle.
9. In a banding tool, the combination with a lever provided intermediate its ends with a downwardly extending jaw adapted to constitute a support for said tool; of a swinging arm pivoted to said lever; a disk pivoted in the outer end of said arm, said disk having a segmental portion constituting a jaw adapted to co-operate with said first mentioned jaw and also having a segmental portion provided with a toothed periphery; a pinion wheel meshing with said toothed periphery; pawl and ratchet mechanism for driving said pinion; and an operating lever pivoted to said first-mentioned lever and arranged to operate said pawl and ratchet mechanism.
10. In a banding tool, the combination with a lever provided intermediate its ends with a downwardly extending jaw adapted to constitute a support for said tool; of a swinging arm pivoted to said lever; a disk pivoted in the outer end of said arm, said disk having a segmental portion constituting a jaw adapted to co-operate with said first mentioned jaw and also having a segmental portion provided with a toothed periphery; a pinion wheel meshing with said toothed periphery; pawl and ratchet mechanism for driving said pinion; an operating lever pivoted to said first mentioned lever and arranged to operate said pawl and ratchet; a catch for securing said swinging arm in position to bring said toothed periphery into engagement with said periphery; and means for releasing said catch.

In witness whereof I hereunto subscribe my name this 28th day of December, A. D., 1911.

ARTHUR M. WIGHT.
